UNITED STATES PATENT OFFICE.

FRANKLIN J. WRIGHT, OF OAKLAND, AND JAMES L. BAKER, OF BAKERSFIELD,
CALIFORNIA.

STANDING-VALVE ATTACHMENT FOR OIL PUMPS.

Application filed January 20, 1921. Serial No. 433,681.

To all whom it may concern:

Be it known that we, FRANKLIN J. WRIGHT and JAMES L. BAKER, citizens of the United States, residing at Oakland and Bakersfield, respectively, in the counties of Alameda and Kern, respectively, and State of California, have invented certain new and useful Improvements in Standing-Valve Attachments for Oil Pumps, of which the following is a specification.

Our invention is an improved oil well pump which is simple in construction and positive and efficient in its operation.

Referring to the annexed drawing in which our invention is illustrated and which forms a part of this specification.

Figure 1 is a vertical longitudinal section of an oil well with our pump mounted therein.

Figure 2 is a view partly in longitudinal section and partly in elevation of our pump.

Figure 3 is a longitudinal section of our pump.

In the drawing, 1 indicates an oil well casing provided with perforations 2 in its lower end for the admission of oil. In the well casing 1 is mounted the usual oil well pump casing 5 in which our pump 6 is detachably mounted.

Our pump includes a casing 7 which slidably fits within the pump casing 5. A head 8 screws into the lower end of said pump casing and has an opening 9 therein through which extends a tube 10. A conical mouth 11 is coupled to the lower end of the tube 10 by a coupling 12 which screws onto the lower end of the tube and on the upper end of the mouth, said mouth being adapted to rest upon a conical sleeve seat 13 in the lower end of the pump casing 5. On the upper end of the tube 10 is mounted a valve 14, which includes a cage 15, a sleeve 16 screwed into a threaded opening 17 in the bottom of said cage, and provided with seat 18 and a ball 19 adapted normally to rest on said seat; said valve being coupled to the tube 10 by a coupling 20 which screws on the upper end of said tube and on the lower end of the sleeve 16 against an external flange 21 on

said sleeve which sleeve also engages the lower end of the cage 15. The coupling 20 and flange 21 fit the interior of the casing 7 closely to prevent oil above the valve 14 from dropping back into the casing. A valve 25 is connected to the upper end of

the pump casing 7, which valve comprises a cage 26 which screws into the upper end of said pump casing, and a ball 27 which normally rests on a seat 28 in said cage and closes the upper end of the pump casing. On the top of the cage 26 is formed a threaded stud 29. A plunger rod 30 extends downwardly through the pump casing 5 and has an enlarged internally threaded end 31 which screws on the stud 29.

As the rod 30 is reciprocated, the valve 25 and pump casing 7 are moved up and down, the mouth 11, tube 10 and valve 14 remaining stationary. As the valve 25 moves upwardly away from the valve 14 on the suction stroke of the pump, a partial vacuum is created in the increased space between said valves and oil is drawn from the well through the mouth 11, tube 10 and valve 14 which opens, into said space. The oil in passing through the tube 10 has a high velocity imparted to it, so that all gravel and sand is thrown clear of the ball 19, which prevents any possibility of said ball sticking in the cage 15. When the valve 25 moves downwardly on the compression stroke of the pump, the oil between said valve and the valve 14 is forced upwardly by the piston action of the coupling 20 and flange 21 through the valve 25, (the ball 27 lifting off its seat) into the pump housing 5 above the pump 6. Continued operation of the pump in this manner pumps the oil out of the well through the pump casing 5.

The pump may be withdrawn from the casing 5 by pulling upwardly on the plunger 30 after it has been pulled to the end of the stroke of the pump so that the head 8 engages the coupling 20.

Having described our invention, we claim:

In an oil well pump, an outer pump casing, an inner pump casing slidably in said outer casing and closely fitting said outer casing, a valve controlling the upper end of said inner pump casing, a plunger rod connected to the top of said valve and extending through the top of said outer pump casing, a head screwed into the lower end of said inner casing and provided with an opening therethrough, a tube extending loosely through said opening into said inner casing, a conical mouth, a threaded coupling which screws on the lower end of said tube and the upper end of said mouth, a seat in the lower end of said outer casing upon which said

mouth is adapted to rest, a valve consisting of a cage having a threaded opening in the bottom thereof, a sleeve adapted to be screwed into the threaded opening, a valve seat and a ball adapted to normally rest in said seat and a coupling to connect the tube to the valve, a flange on the sleeve, the cou-

pling and flange closely fitting the interior of the casing to prevent oil dropping back into the casing.

10

In testimony whereof we affix our signatures.

FRANKLIN J. WRIGHT.
JAMES L. BAKER.
